WHIRLING MUSICAL TOY OR
SIMILAR ARTICLEElmer W. Swanberg, 1420 E. 58th Ave.,
Spokane, Wash. 99203

Filed July 23, 1969, Ser. No. 18,350

Term of patent 14 years

Int. Cl. D21—02

U.S. Cl. D34—15

FIG. 1 is a right front perspective view of the whirling musical toy or similar article embodying my new design, as viewed from the bottom; and

FIG. 2 is the musical game toy or similar article taken from the side opposite FIG. 1, as viewed from the top.

I claim:

The ornamental design for a whirling musical toy or similar article, substantially as shown and described.
